UNITED STATES PATENT OFFICE.

BELLE B. TEN EYCK, OF BRIDGEPORT, CONNECTICUT.

DESIGN FOR A CLOTHESHANGER.

Application filed August 26, 1922. Serial No. 3,571. Term of patent 7 years.

To all whom it may concern:

Be it known that I, BELLE B. TEN EYCK, a citizen of the United States, and a resident of Bridgeport, in the county of Fairfield and State of Connecticut, have invented a new, original, and ornamental Design for a Clotheshanger, of which the following is a specification, reference being had to the accompanying drawing, forming a part thereof, and in which the figure is a perspective view of a clotheshanger showing my new design.

I claim:

The ornamental design for a clothes-hanger as shown.

Signed at Westerly, in the county of Washington and State of Rhode Island, this 19th day of August, A. D. 1923.

BELLE B. TEN EYCK.
